BOTTLE

Samuel L. Gerson, Wilmington, Del.

Application March 29, 1955, Serial No. 35,254

Term of patent 14 years

(Cl. D58—9)

FIG. 1.

FIG. 2.

FIG. 3.

Fig. 1 is an elevational view showing one face of the bottle of my new design;

Fig. 2 is an elevational view of the bottle as viewed from the left-hand side of Fig. 1, and

Fig. 3 is an elevational view showing the opposite face of the bottle from that illustrated in Fig. 1.

I claim:

The ornamental design for a bottle, substantially as shown.
